UNITED STATES PATENT OFFICE

LYDIA PEARL KREY, OF EUGENE, OREGON

TRAY

Application filed July 19, 1929. Serial No. 379,349.

This invention relates to trays or baskets adapted to be used for display purposes or for serving, and while it is more especially designed for use in the manufacture of ornamental trays it is applicable to trays of other kinds to be used for various purposes. The primary object of the invention is to provide a tray having a solid base or bottom provided with a plurality of marginal apertures 5 through which are passed a plurality of weaving reeds so as to form a marginal upstanding flange extending completely around the periphery of the tray to retain objects thereon and to impart an ornamental appearance 10 to the same.

A still further object of the invention is to provide a tray having a rigid bottom and a border formed by woven reeds extending thru the bottom of the tray so as to form an ornamental upstanding rim and a resilient marginal rest upon which the bottom is supported to protect the supporting surface upon which the tray rests from being defaced.

Still further objects of the invention are 25 to provide a tray which is extremely attractive in its appearance, but which is strong and durable and one which will withstand hard usage. Convenience of arrangement of parts, lightness, strength and comparative in- 30 expensiveness of manufacture are further desirable features that have been borne in mind in the production and development of this invention.

With these and many other objects in view 35 which will more readily appear as the nature of the invention is better understood, the same consists in the novel construction, combination and arrangement of parts shown in the accompanying two sheets of drawings in 40 which:

Figure 1 is a top plan view of the assembled tray constructed in accordance with this invention.

Figure 2 is a side view of the tray.

Figure 3 is a detailed fragmentary side view of the tray showing the manner in which the wicker border is woven through the tray bottom.

Figure 4 is a fragmentary side view similar 50 to Fig. 3 which shows the strands of the re-

taining rim removed in order to reveal the construction of the retaining border.

Figure 5 is a fragmentary plan view of the bottom of one edge of the tray.

Figure 6 is a sectional view of the wicker 55 rim of the tray; and

Figure 7 is a sectional view taken substantially along the line 7—7 of Fig. 6.

In all of the above described views like characters of references are employed to designate like parts throughout and the tray consists of a bottom 10. This bottom may be constructed in any suitable shape such as the suits of a deck of cards and of any desirable material such as wood or the like. In this 60 particular embodiment of the invention, the tray is shown as being of diamond shape to represent one suit of the ordinary deck of playing cards, it being contemplated to provide other trays similar in design and to represent the other three suits, namely, the hearts, 65 spades and clubs of the deck.

The bottom 10 is provided with two acute angle and two obtuse angle corners 12. A plurality of equi-distance spaced holes are 70 drilled, punched or otherwise cut thru the bottom 10 around the periphery thereof. These holes are designated at 14. The tray is provided with a peripheral border designated in its entirety at 15. This border is 75 comprised of a number of woven strands of resilient material woven through the holes 14, and upon themselves in a novel manner.

The peripheral border comprises a plurality of vertical loops 22 formed of strands 80 which pass through the holes 14 and which are woven upon each other as at 17 to provide a peripheral base upon which the tray may be placed. The tray is most conveniently formed by hand weaving and it is 85 preferred to position the strands forming the loops 22 as the first step in the manufacture of the tray. Accordingly a plurality of strands 46, 48 and 50 respectively are passed through consecutive holes 14 from the upper 90 side of the tray and are carried thru the tray until a sufficient length remains to form equal loops 22 on the upper side of the same. The upper ends of each strand is temporarily 95 permitted to remain free as shown by dotted 100

lines at 51 in Fig. 4. The portion of each strand which has been passed thru the tray is then bent at right angles to the sides of the loop 22 and passed along the edge of the bottom 10 and woven together in the manner clearly shown in Figure 5. Consecutive strands are designated at 46, 48 and 50. Each of these strands extends thru a hole 14 and is passed under an adjacent strand at the point where the adjacent strand emerges from its respective hole 14 and thus all of the strands are firmly held against the bottom 10 so as to provide a peripheral base 17 upon which the tray rests.

15 When the peripheral base 17 has been formed the free ends of the strands 46, 48 and 50 are brought into the position shown in full lines in Fig. 4 so that the end of each strand abuts against the bottom 10 adjacent the hole 14 through which the next strand passes. The strands 46, 48 and 50 are then held in place by a plurality of interwoven strands designated at 32, 34, 36, 38, 40, 42, 44, 45 and 47. These strands are woven in and about the vertical portions of the strands 46, 48 and 50 which form the loops 22. These strands serve to hold the loops 22 in their proper form and the weaving operation may be performed in any suitable manner. However, it is preferred that strands in addition to being woven in and about the vertical portions of the loop 22 be woven together in groups of three, as clearly shown in Figs. 2 and 3. The upper group is designated at 60 and comprises the strands 32, 34 and 36. The middle group is designated at 62 and comprises strands 38, 40 and 42 and the lower group is designated at 64 and comprises the strands 44, 45 and 47. The strands which comprise the group 60 are separate and independent from the strands which form the group 62. The design of the tray may be varied by spacing these groups of strands from each other without destroying their utility, each of the groups 60, 62 and 64 being slidably vertical on the vertical portions of the strands 46, 48 and 50. A pair of handles 16 are provided on the tray. These handles are in the form of upwardly and outwardly bent loops of wicker material slightly heavier in construction than the material used for the border. These handles are secured to the tray bottom in any suitable manner, as for example by gluing or tacking their ends into the holes formed in the tray bottom 10. The vertical portions of the handles pass between adjacent strands of the groups of strands 60, 62 and 64. The free ends 51 (see Fig. 4) of the strands 46, 48 and 50 are discontinued as loop forming elements between the ends of each handle and these free ends are utilized to hold the groups of strands 60, 62 and 64 in position by weaving in and about the same as clearly shown at 58 in Fig. 1.

65 The above mentioned parts are believed to

adequately define the nature of this invention and the tray, when completed, comprises the base 10, the peripheral support 16 beneath the base which is formed by passing the strands from which the loops 22 are formed 70 through the base. The strands forming the groups 60, 62 and 64 serve to retain the loops in position and also serve to form a closed wall about the periphery of the tray to retain objects thereon.

75 It is of course to be understood that in forming the tray, if the border is to be formed of wicker material, it is desirable that strands used be first soaked in water to soften the same to facilitate the weaving operation.

80 Various modifications in the specific design of the wicker work may be made and the method of weaving may be altered without departing from the spirit of my invention or the scope of the appended claims 85 which are intended to cover broadly and specifically a tray formed of a perforated base with a wicker rim above the base and a wicker support below the base by weaving the wicker through the perforations in the base.

90 What I claim is as follows:

95 1. A tray of the character described comprising a perforated bottom; a plurality of strands of resilient material threaded through said bottom and extending above the same to form a plurality of open loops adjoining each other as a border for the tray, each of said loops being formed of a single bent over strand, one end of said strand extending through one of the perforations in 100 the bottom, and the other end of said strand held in position by contact with the strand of the next adjacent loop, said strands that extend through the bottom being woven together beneath the bottom to form a support 105 for the tray; and a plurality of additional strands of resilient material woven together and around the strands threaded through said perforated bottom to reinforce the same.

110 2. A tray of the character described comprising a perforated bottom; a plurality of strands of resilient material threaded through said perforations, said strands extending above the bottom to form a peripheral border of adjoining open loops for the tray, each strand being formed of two bent over portions, one of these bent over portions passing through one of the perforations in 115 the bottom, and the other of said bent over portions being held in contact with the strand of the next adjoining loop, said strands being woven together beneath the tray to form a support therefor; and a plurality of additional strands of resilient material woven together and through the strands of said peripheral border to reinforce the same.

120 3. A tray of the character described comprising a perforated bottom; a plurality of strands of resilient material threaded 125

through said perforations, said strands extending above the bottom to form a peripheral border of adjoining open loops for the tray, each strand being formed of two bent over portions, one of these bent over portions passing through one of the perforations in the bottom, and the other of said bent over portions being held in contact with the strand of the next adjoining loop, said strands being woven together beneath the tray to form a support therefor; a plurality of additional strands of resilient material woven together and through the strands of said peripheral border to reinforce the same; handles for said tray extending through said last mentioned woven strand and into the tray; certain of said first mentioned strands having their ends woven through said reinforcing strands to maintain the reinforcing strands in position upon said bottom.

20 In testimony whereof I have affixed my signature to this specification.

LYDIA PEARL KREY.
